COMPUTER TERMINAL ACOUSTIC COVER

Charles H. Scott, Box 5242, Station "F,"
Ottawa 5, Ontario, Canada

Filed Apr. 21, 1972, Ser. No. 246,512

Claims priority, application Canada Oct. 26, 1971

Term of patent 14 years

Int. Cl. D14—02

U.S. Cl. D26—5

FIG.1

FIG.3

FIG. 1 is a perspective view of a computer terminal acoustic cover showing my new design;

FIG. 2 is another perspective view thereof showing the inclined panel in an open position; and

FIG. 3 is a bottom plan view thereof.

The broken line representation of a computer terminal in FIGS. 1 and 2 is for purposes of illustration only.

The rear of the cover is plain and unornamented.

I claim:

The ornamental design for a computer terminal acoustic cover, as shown and described.
